SHAVING MACHINE

John T. Scully, Lawrence, N. Y.

Application March 9, 1942, Serial No. 433,973

16 Claims. (Cl. 30—43)

This invention relates to shaving machines of the kind usually employed to cut hair without the use of shaving preparations, such machines being commonly referred to as dry shavers.

The present invention relates more particularly to shaving machines employing co-operating shearing members, and subject matter of this invention is related to matter disclosed in my co-pending application Serial Number 246,036, filed December 16, 1938, for Shearing device; my co-pending application Serial Number 404,536, filed July 29, 1941, for Shaving machine; and my co-pending application Serial Number 433,972, filed simultaneously herewith for Shaving machine.

A principal object of the invention is to provide a dry shaving head of generally improved efficiency, the parts of which are easily, cheaply, and accurately manufactured.

A further principal object is to provide a dry shaving head the parts of which are precisely made and easily and accurately assembled.

A further principal object is the provision of an especially efficient dry shaving head for individual self-use, professional and institutional use.

A further principal object is the provision of a simply made, improved dry shaving head employing a rotary cutter.

A further important object is the provision of an improved shearing head radially arranged relative to the handle of the machine. A further object is the provision in an arcuate outer shear member seated on an arcuately travelling inner cutter of a plurality of elongated hair-receiving slots arranged in a row which is directed in a direction transverse to the direction of curvature of the member in combination with a series of comb teeth bearing on the outer surface of the member. Further objects are improvement in parts of arcuate outer shear members movably held forcibly seated on an inner cutter; improvement in holding and forcing means parts; improvement in co-operative engaging parts of outer shear members; and protective parts for holding and forcing means.

Further important objects in the provision of a shearing head having an arcuate outer shear member and an arcuately travelling inner cutter are the provision of improved means to removably hold either of a plurality of outer shear members out of frictional engagement with an inner cutter; an improved dual shear-cutting head; an improved arrangement and combina-

tions of openings in outer members of a dual head.

Other objects will be apparent from the drawings and description thereof.

5 The invention resides substantially in the construction, combination, arrangement, relative location of and co-action of parts as will be described in connection with the drawings.

I wish it to be understood that any or all of 10 the parts may be made of any suitable material or materials and that some or all of the parts or portions of the parts may be made of a metal such as steel, or other metals, or any alloy or alloys thereof; that some or all of the parts, or 15 portions thereof, may be formed of metal having any desirable and suitable composition of ingredients and that such metal may be mechanically worked and/or heat treated and cooled according to the best practice in this art or in

10 the art of metallurgy at any time prevailing; that some of the parts, or portions thereof, may be made of rigid or resiliently flexible metal or other suitable material; and that the metal may 20 be provided with such qualities and degrees of hardness, ductility, strength and corrosion resistance as may be deemed best suited and practicable; and further, that the parts are made 25 and assembled with care and precision and mechanical skill as is desired in instruments of this kind.

30 In the preferred embodiment of the invention shown for illustration the movable inner shear member which I refer to as the inner cutter or inner cutter member is rotated continuously in one direction and is provided with edges which are adapted to co-operate with edges of one of several outer shear members which outer shear members are provided with suitable hair-receiving openings to admit hair to be shorn by the co-operation of the respective edges; however, in the broad sense, the invention contemplates the use of any suitable inner cutter or cutters, for example the use of an inner cutter, 35 which is moved alternately back and forth, and also contemplates the use of a single outer shear member. The preferred embodiment of the invention contemplates the inclusion of several outer shear members in a single shaving head for convenient use on different portions of the

40 skin, for shear cutting long hair, relatively long hair, short hair, and for close shaving, and which are simply and quickly detachable from the device for purposes of sterilization, cleaning, inspection and the like. Further, the present invention 45 contemplates the use of a single outer shear member. The preferred embodiment of the invention provides for a shaving machine, a dry

50

shaving head in which one of several outer shear members may be omitted in commercial use for reasons of costs, or temporary scarcity of suitable materials, or during sterilization, or as a result of damage or other reasons, without preventing use of the machine and without danger to the user, the operator, or the person whose hair is being cut.

Figure 15 is an enlarged fragmentary plan view of a modification of parts.

Referring again to the drawings of a preferred embodiment of the invention and in more detail, and with particular reference to Figures 1 to 8 inclusive, the reference character H denotes generally, a casing, usually made in several parts suitably joined and of molded material such as "Bakelite" or other similar material, and which is the basic support for the head portion of the device; is the housing for the electric motor for actuating the inner cutter member; and, also, serves the purpose of a handle for the device, such combined handle and housing being well known in the art. The handle-housing portion of the device is elongated and its major portion may be in cross-section of generally cylindrical shape, or of generally conical shape, suitably rounded at its longitudinal lower or outer end, and provided in its upper region with an inwardly sloping circumferential shoulder 1 merging with a relatively narrow necked-in portion 2 long enough to receive, if desired, a finger or two of the user. Projecting radially from the

necked-in portion is a generally circular platform-base portion 3 to which the rigid rear wall 4 of the cutting head is secured by suitable means such as the screws 5. This rear wall is provided with diametrically opposed portions 6 flat on their inner face and projecting radially and somewhat less than semi-circularly from the platform-base, and on which in diametrically opposed regions are radially projecting portions 7 of relatively narrow width terminating in perpendicular portions 8 which by suitable means such as offset screws 9 are detachably secured to similar perpendicular portions 10 of radially projecting relatively narrow portions 11 on diametrically opposed portions 12 of the rigid forward wall member 13. Thus, the two wall members 4 and 13 together with their connected bridging portions 8 and 10 constitute a rigid, accurately made and accurately aligned guard structure for the inner cutter member, this guard structure being generally denoted by the reference character W and having, preferably, considerably greater diameters than the width of the space between the inner parallel faces of the wall portions 6 and 12. Mounted for rotary travel between the planes of the walls of the guard structure W is a rotary cutter member generally designated by C, the peripheral cutting ends of which project radially outwardly of the arcuate ends of the somewhat less than semi-circular portions 6 and 12 of the guard structure W but which are spaced from the under or inner sides of the connecting or bridging portions so as to pass underneath these latter portions during rotation with suitable clearance. The inner cutter may be any suitable cutter member, but in its preferred form is similar to the rotary cutter members shown and described in the aforementioned co-pending applications and comprises a plurality of elliptical blades having longitudinally spaced obliquely projecting portions, diametrically opposed cutting portions, and cutting edges at the peripheral side ends of the cutting portions. Usually the cutter member is an assembly of relatively thin, flat bodied, elliptical shaped metal blade elements 14 having continuous peripheries 15 parallel and flat to a cylindrical plane and continuous sharp edges 16 at opposite sides of the peripheries. On one or the other of, depending upon the direction of rotation, opposite sides of the peripheries of the diametrically opposed portions these edges or portions thereof are cutting edges. The elliptical blade elements project radially outwardly of, and are spaced to provide hair-receiving slots in parallel, oblique, straight planes by suitable spacing elements 17, which, also, are preferably elliptically shaped, and the end blades are backed up by end elements 18 having oblique inner faces and perpendicular outer faces, the end elements tapering in cross-sectional thickness. The blade elements, spacing elements and end elements are centrally provided with suitable openings for the reception of, and are mounted on, a rotatable shaft of suitable shape in cross-section and which may be either solid or tubular, and as shown herein are mounted on a cylindrical shaft 19, the elements of the assembly having centrally disposed elliptical openings and the assembly being secured at their longitudinal ends by nuts 20 threadedly engaging the shaft, and preferably nuts of the lock variety, or, if desired, by nuts held or locked by pins, for example cotter pins. Usually to facilitate accurate assembly of the blade and spacing elements

and to secure the elements against individual relative rotary movement, a longitudinally extending key-way is provided in the shaft into which is fitted a longitudinal key 21 which is received in slots in the walls of the blade and spacer elements surrounding the walls of the central openings, these slots connecting with or being a narrow extension of the elliptical openings. The blade elements have the same axial dimensions, their peripheries are carefully, and accurately ground, and their peripheries and side portions adjacent the peripheries are usually lapped, and their projecting portions are relatively rigid to withstand pressure during operation and remain in their normal planes. In the preferred form of the machine in which the axis of rotation of the cutter is continuous with, or parallel to, the longitudinal axis of the handle-housing, the inner cutter member travels a rotary path on a relatively large radius, for a concrete example a radius between one and 1½ inches, a good radius being 1½ inches, and the radius of the cutter is preferably greater than one-half the thickness of the handle so that the former projects radially outwardly and laterally of the plane of the handle. The cutter rotates on a conical forward pivot bearing 22 secured in the forward wall 13 and in a sleeve bearing 23 secured in the rear wall 4 of the guard structure W, and the cutter shaft may be integral with an electrically revolved motor shaft, or, as shown, be detachable therefrom in the form of a short shaft axially aligned with and rotatable by the motor shaft. In the form shown the cutter shaft is provided with a projecting key 24 centrally disposed on the inner end of the shaft 19 and having bevelled marginal end portions 25 to facilitate insertion of the key portion into a slot in the outer end of the motor shaft with the end face of the key against the slot wall 26 and with the end faces of the shafts lateral of the key and slot against each other. Marginal end portions of the respective shafts are received in a rotatable sleeve or collar 26a which is secured to and rotatable with the motor shaft by any suitable means, such as a pin or stud, or, as shown, by a rivet 27. The inner cutter may, for lightness of weight, be made hollow in cross-section, for example in the form of a tubular member with radially projecting blades, and may, if desired, be provided with radial blades integral with a hollow or integral with a solid shaft.

An outer shear member to co-operate with the inner cutter member is generally designated by the reference character P. This shear member is preferably considerably longer than its width and is made of extremely thin, resilient metal, preferably from rolled steel strip or sheet or suitable alloy of steel. At opposite marginal longitudinal ends and on the outer face thereof the member is provided with stiffening members 28 which extend for the full, or approximately full, width of the outer face of the shear member and which preferably have their inner end faces bevelled or rounded, and inclined as shown. The stiffening members are relatively rigid and may be secured to the shear member by any suitable means. For example by soldering or welding, or, if desired, by rivets so positioned as to provide sufficient space between their inner ends and the peripheries of the cutter for cutter clearance and for a further purpose which will hereinafter be apparent. The outer shear member is longitudinally flexed to arcuate form in engagement

with the peripheries of the inner cutter member and with the stiffened opposite marginal longitudinal portions extending in divergent flat, or substantially straight, planes so that opposite 5 marginal longitudinal end portions 29 of the inner face of the shear member are substantially tangential to the arc of the cutter path, or cutter peripheries and diverge therefrom in the direction to the ends of the member. At the longitudinal ends of the outer shear member the stiffening members are provided with outwardly and forwardly turned or bent rigid end portions 30 to provide longitudinal grooves transversely on the member for the reception of holding and 10 forcing bars 31 which are preferably cylindrical in cross-section and at opposite longitudinal ends are provided with flanged ends in the preferred form of circular discs 32. The turned or bent end portions may be curled, but preferably are formed 15 to provide concavely curved wall portions at the inner end sides of the grooves to snugly accommodate the bars and from which curved wall portions the inner faces of the groove walls extend in divergent straight planes progressively 20 widening the groove outwardly. The holding and forcing bars are attached to tensed helically coiled springs 33 the bars being long enough relative to the width of the shear member and the width of the guard structure W in this region to 25 receive at each flanged end of the bars hooked or looped fastening portions 34 at one end of the springs; the opposite ends of the springs are provided with U-shaped fastening hooks 35 which are received in annular apertures 36 of the forward and rear walls of the guard structure and hooked against the material of the walls thereby holding the springs expanded under the desired tension. The fastening portions of the springs may be rigid members attached to the 30 springs or integral parts thereof. These springs acting upon the bars hold the shear member flexed and bearing against the cutter and exercise a pull the direction of which serves to pull the shear member radially inwardly and at the 35 same time flex the member radially inwardly to reduce its radius of curvature as wear of the shear-cutting members occurs so that the same amount of area of the member continues to bear against the cutter. The springs are expanded 40 in parallel or approximately parallel, planes and exercise an even and parallel pull on opposite sides, each spring of a pair exerting the same, or approximately the same, force as the laterally opposite other spring of the pair, and, as intended 45 to be shown herein, the relative locations of the apertures 36 are so arranged as to cause the springs to exercise the proper directional pull, which, it may be said, is in the direction of a resultant of forces acting to simultaneously pull 50 and flex the outer shear member radially inwardly. Additional apertures 36a adapted to receive the fastening portions of the springs are preferably provided for purposes of altering the direction of pull, increasing the tension, or compensating for inward movement, because of wear, 55 of the outer member, or general readjusting purposes; additional apertures adapted to receive the fastening portions 35 of the springs may desirably be provided in the walls radially outwardly 60 of the apertures 36 for similar purposes and also to relieve tension of the springs for reasons which will hereinafter be apparent; further additional apertures may be provided variously distributed in the forward and rear walls of the guard structure 65 W for purposes of air-cooling the head. The 70

coils of the springs are preferably encased in an expandable sleeve 36b of suitable yielding material in relatively thick folds, for expansion purposes longitudinally and gathered in at opposite ends to neck portions sewn or laced. Soft, pliable leather is a good material and is relatively durable. These telescopic sleeves prevent hair from being caught by the springs and serve to protect them from damage, the sleeves being thick and firm enough and the cross-section of their interiors relatively large enough to prevent the material from being caught between the coils of the springs. If desired, spring covers can be made in tubular form of a hard material, or a hard and rigid material. To remove the outer shear member from the machine for any reason, the flanged ends of the bars are gripped by the fingers, the circular disc ends providing comfortable and convenient portions for gripping, and the bars are pulled radially out of their nesting grooves and pivotally swung into nesting longitudinal grooves 37 which are provided in the outer surfaces of the connecting or bridging portion 8 of the projecting portions 7 of the rear wall as shown. Release of the end or ends of the member from the pressure of the bars unflexes the member so that the ends spring outwardly as the member returns to its normal straight or approximately straight plane, the user of course seizing the member to prevent its accidental fall. The member, then, is insertable radially and removable radially, and the spring elements hold it movable radially outwardly as a whole, and, as wear occurs, movable radially inwardly as a whole. The outer shear member P is provided along the arcuate portions of its opposite longitudinal sides with radially and inwardly projecting narrow fingers 38 which taper diminishingly in width in the direction of their free ends and extend in planes parallel with, or substantially parallel with, the inner faces of the wall portions 6 and 12 and with marginal end portions of the fingers received in the space between these wall portions, fitting closely therein and preferably with their outer lateral faces in frictional engagement with the inner faces of the walls. Spacing the fingers longitudinally are narrow slots 39, in alternate relation with the fingers. At opposite longitudinal ends of the finger and slot arrangement on each side of the member and having preferably the same thickness as the fingers, are imperforate wall portions which are guard, guiding and positioning walls serving also, as do the fingers, with the walls of the structure W to limit, if not prevent, lateral or transverse movement of the member by its frictional engagement with the skin. The outer portions of the fingers and slots serve as comb bars and hair-receiving slots respectively, the fingers serve as a shield or guard to protect the skin from the cutter, and the arrangement of the fingers and slots serving to facilitate proper longitudinal flexing of the shear member. Any suitable means suitably located may be provided to prevent or reduce the tendency of the outer shear member to be pulled by the cutter peripheries in the direction of cutter rotation, for example one pair of the set of springs resiliently holding the member may be made to exert a stronger pull than the springs at the opposite end and, or, as shown herein, pins or studs 40 are provided centrally on the walls 6 and 12 and project into slots centrally disposed in the slot and finger arrangements on opposite longitudinal sides of and

centrally of the length of the member, the pins or studs having their projecting portions in engagement with fingers on both sides of the slots or with fingers on one side of the slots, any suitable means such as markings may be made on the member to visually identify and locate the central slots. The member is conveniently seated by locating the central slots in line with the studs while the member is unflexed, then bending the fingers on opposite sides of the member in the central region towards opposite sides as by squeezing, then progressively squeezing the fingers and progressively flexing the member on the cutter on opposite sides of the central region out to the ends; then holding the member seated in flexed form and swinging the holding and forcing bars into the grooves on the member. This operation can be facilitated by providing inwardly partially curled portions on the extreme marginal ends of the fingers and/or flaring the opening between the walls 6 and 12 by rounding or beveling the inner sides of the walls at the outer end of their inner faces. The fingers 38 have perpendicularly disposed bar portions 41 which are also narrow but preferably of uniform width and which are longitudinally spaced by closed-end slots portions 42, which are perpendicular continuations of the slots 39, these portions of the slots and fingers also serving as hair-receiving slots and comb bars, and the slot portions 42 being all the same, or approximately the same, length. At the closed ends of the slots on the inner surface side of the shear member the walls which constitute the closed ends of the slots meet the inner surface of the member at shearing edges which edges co-operate with peripheral cutting edges on the inner cutter to shear-cut hair caught between. These shear edges at the inner ends of the slots may be on a U-shaped curve; or longitudinal edges acutely inclined to the axis of cutter rotation and parallel to the planes of the cutting edges of the inner cutter; or they may be longitudinal edges acutely inclined to the axis of cutter rotation and to the planes of the cutting edges of the inner cutter; as shown here these shear edges of the outer member are rectangularly disposed to the axis of rotation of the cutter and the cutting edges of the inner cutter member are acutely inclined to the shear edges of the outer member. The narrow transverse comb bars and slots arranged on opposite longitudinal marginal sides of the arcuate outer shear member provide for the easy entrance of long, relatively long, and short hairs into the slots especially so when the machine is moved on the skin in a direction, or in opposite directions, continuous with the slots, or when the head is rolled or rocked on the skin. For reasons which will later be apparent the outermost blade of the inner cutter member is positioned closer to the radially inwardly projecting finger portions on the corresponding longitudinal side of the outer shear member than is the innermost blade to the projecting portions of the fingers on the inner longitudinal side of the outer member; the inclination of the blades is such relative to the relatively long radius of the cutter that portions of their peripheries pass suitably far laterally outwardly of the co-operating shear edges to provide a slot-like opening therebetween of suitable length and pass suitably far laterally inwardly of the shear edges to effect the desired clean and complete shear-cut therewith and completely open up the slots. In the outer shear member P through the

arcuate portion intermediate the longitudinal rows of slots and fingers are formed a plurality of small closely spaced hair-receiving openings. These openings may have any suitable shape, such as annular, square, oblong or general triangular. In their preferred form they comprise very short equi-sized closed-end slots 43 having their long dimension directed transversely to the direction of curvature of the member and preferably parallel to the axis of the outer member and in planes parallel to the longitudinal axis of the handle and the machine as a whole and because of the extreme thinness of cross-section of the member in the area of these small openings the slots 43 may have a length only slightly greater than their width; these slots may be of uniform width for any suitable portion of their lengths; as shown here they are of uniform width and rectangular in shape, but, if desired, their opposite longitudinal ends may be curved, or may parallel the cutting edges of the inner cutter, and are arranged in transversely spaced, parallel, longitudinal rows and the rows extend longitudinally to within a very short distance of the stiffening members 28. Preferably, the rows are closely and uniformly spaced transversely; and there may be any suitable number of such rows. In each row the slots are very closely spaced longitudinally by short, narrow, extremely thin, transverse bar portions formed in the outer member in the making of the slots; and the location of slots in the rows relative to slots in adjacent rows is such as to dispose the longitudinal axes of individual slots in a row slightly laterally longitudinally to the longitudinal axes of individual slots in adjacent rows, with the result that during a given stroke or manipulative action of the machine on the skin good opportunity for hairs to enter the slots is provided, particularly short or relatively short hairs; and this opportunity is further increased by the considerable number of rows of slots and the narrowness of the bars. The slots are formed in a manner which provides sharp inner edges on the material of the member, these edges constituting opposite ends and sides of the innermost part of the individual slots, and are formed in manufacture preferably while this portion of the member is in a flat plane and formed so that the walls of the slots are perpendicular to the inner surface of the member and meet the inner surface of the member at sharp rectangular edges. Hairs entering these openings and the spaces between the inner cutter blades are shorn, in the preferred embodiment, at either or both ends of the slots and/or marginal ends, during rotation of the inner cutter member. These closed-end slots 43 are directed transversely and rectangularly to the direction of curvature of the shear member P and their axes are in planes paralleling the longitudinal axis of the handle-housing and machine as a whole, and are especially adapted for the reception of short and relatively short hairs when the machine is moved in a direction, or in opposite directions continuous with the slots and the axis of the handle-housing and the direction of hair-growth; or when the head is rolled or rocked on the skin in the direction of curvature of the outer shear member and transverse to the longitudinal axes of the slots, and transverse to the direction of hair-growth.

The outer shear member P may be made of uniform thickness for its entire width between the stiffened, relatively rigid portions 28, but generally I prefer to reduce the thickness of the

strip of metal intermediate the oppositely disposed rows of fingers so that the thickness of the material throughout the area of small openings, while uniform or substantially uniform, is 5 thinner than the material constituting the fingers; this difference in thickness may be extremely slight and result from grinding and polishing operations performed on the outer surface during manufacture, or the difference in thickness may be substantial at greater cost and 10 whereby the widths of the slot portions 42 may be increased to further facilitate entrance of hair. The grinding operations may be carried out in a direction longitudinally of the member or transversely thereon with the result shown in Fig. 6 in which the outer surface of the upper finger portions slopes at their inner ends as designated by X to the lower plane of the material on whose inner side are provided the edges at the 15 inner ends of the slot portions 43 and at the ends of the slots 43. It will be apparent that the shape of the outer surfaces of the shoulders X may be a bevelled slope or a concave slope depending upon the direction in which the grinding operations are carried out. To provide edges 20 efficient for picking up hairs and erecting them for entrance into the slot portions 42 the outer faces of the radial fingers may be notched as shown by the dotted line 41m providing hair- 25 gaging edges 41n at the outer corners.

It will be observed that the outer shear member P is reversible endwise so that after removal for any purpose the member may be reinserted without confusion or error or altering its co-operative action with the inner cutter member.

Disposed on the opposite side of the shearing head and radially opposite to the shear member P is another outer shear member P'. The member P' is provided along the arcuate portions of 30 its opposite longitudinal sides with radially and inwardly projecting narrow fingers 38a which taper diminishingly in width in the direction of their free ends and extend in planes parallel with, or substantially parallel with, the inner faces of the wall portions 6 and 12 and with marginal end 35 portions of the fingers received in the space between these wall portions, fitting closely therein and preferably with their outer lateral faces in frictional engagement with the inner faces of the walls. Spacing the fingers longitudinally and in alternate relation therewith are narrow slots 39a the outer ends of which extend only a short distance laterally into the member to permit proper flexing thereof. Intermediate the longitudinal rows of fingers 38a and slots 39a are formed a 40 plurality of small, closely spaced hair-receiving openings. These openings may have any suitable shape; in their preferred form they comprise short equi-sized closed-end slots 44 having their 45 long dimension directed in the direction of curvature of the member in planes perpendicular to the axis of rotation of the cutter and perpendicular to the longitudinal axis of the handle and the machine as a whole. The end longitudinal rows said slots on opposite transverse sides of the 50 member are as near their respective side ends of the member as is practicable in order that the openings in these regions may be used to receive hairs of the "sideburns," since this outer shear member is also endwise reversible. At opposite 55 longitudinal ends of this zone small openings in margins between its ends and the stiffened portions and formed through the material of the member in a manner similarly to the small openings 60 are a plurality of transversely spaced, uni-

formly wide, elongated hair-receiving slots 45, extending in planes in a direction perpendicular to the axis of rotation of the cutter member and continuous with the direction of curvature of the outer shear member. Preferably, the width of the elongated slots is greater than the width of the short slots. Sharp inner edges on the material of the member constitute opposite ends and sides of the innermost part of the elongated individual slots. To facilitate the entrance of long hairs into the slots there are provided comb members 46 having resilient, transversely spaced, longitudinally directed and flexed comb teeth 47 whose free ends 48 are positioned in planes longitudinally spaced a suitable distance from the planes of the inner or forward longitudinal ends of the elongated hair-receiving slots to preferably provide short marginal end portions 45a in the elongated slots which portions are longitudinally ahead of the planes of the free ends of the comb fingers or teeth, the length of these portions of the slots being suitably related to the width of the slots and the height of the ends of the comb teeth to prevent injury to the skin, and the outer surfaces of the comb teeth and comb members increasing in height from the inner edges of the slots in the direction of their outer ends. The comb teeth may have any suitable thickness and may be of uniform thickness, but, as shown herein, they are preferably provided with a thickness which diminishes in the direction of their free ends, and the diminution may, with advantage, be progressive or tapering. In some instances the comb teeth may extend beyond the inner or forward ends of the long slots and terminate on the continuous transverse strips of material which space the long slots from the short slots. The width of the comb teeth is equal to, or approximately equal to, the width of the bars formed in the shear member by the elongated slots which is sufficient to make them strong enough relative to their length and thickness to prevent them being moved sidewise by skin or hair during shaving and entering the slots and, the spacing or the width of the slots between the comb teeth is equal to, or approximately equal to, the width of the elongated slots, so that the comb teeth and inner bars, and the slots of the comb member and the inner elongated slots are respectively in registration. The comb members may be secured to the shear member by any suitable and convenient means such as by screws, or solder, or by welding; as shown their imperforate portions are rigidly secured to the outer faces of the stiffening members 28a so that their resilient comb teeth are flexed with portions of the teeth bearing lightly on the outer surface of the arcuately flexed portion of the outer shear member with the result that as wear of the co-operating shear-cutting members develops the ends of the comb teeth remain in engagement with the outer surface of the flexed outer shear member and prevent hairs from being caught between or wedged between the teeth and the outer surface of the arcuate portion of the outer shear member, or prevent long hairs, or relatively long hairs, from becoming curled around the teeth. It will be apparent that I may provide the comb teeth as continuations of the stiffening members 28a, the comb teeth or portions thereof being resilient portions of the stiffening members, and, further, that the longitudinal shape of the teeth may be an arch with their outer surfaces curving convexly. At their free ends the comb teeth may have any suitable shape, preferably the end

edges and corners on the upper or outer sides are removed as by rounding and on the lower or inner sides the surface may meet the end surface at an edge or, if desired, on a slight curve; transversely, the ends may have straight portions between rounded corners or bevelled corners, or the ends may be continuously curved, as is well known in the art, to facilitate erecting, deflecting and guiding hairs into the slots. The pressure which the tensed comb teeth exert on the arcuate portion of the outer shear member, in this instance on the arched bars formed by the elongated slots, is relatively slight so as to preferably not distort the arcuate planes of the shear edges of the bars or otherwise interfere with the efficient functioning of either of the co-operating shear-cutting members, the pressure being sufficient to prevent the free ends of the comb teeth from being lifted relative to the arcuate surface of the shear member by further flexing of and radius reduction of the latter during wear of the co-operating shear-cutting members. In constructing the outer shear member P' so that the end longitudinal rows of small openings 44 at opposite transverse sides of the member are near enough their respective side ends of the member for efficient use to satisfactorily trim or align the "sideburns," and to simplify its manufacture, I prefer in forming the member, after stamping operations, to accurately bend the fingers 38a to their respective positions as shown, for example as in Fig. 5; however, I may, in manufacture, if desirable, bend longitudinally extending margins of a flat metal sheet or strip to form it channel shaped in cross-section, and then cut slots in the opposite side walls to provide, as in Fig. 5A, fingers 38b whose outer surfaces are flush with the ends of the sides of the shear member P'M, and whose small openings or short slots 44a are spaced the same distance, or substantially the same, from the outer surfaces of the fingers as are the short slots 44 from the outer surfaces of the fingers 38a (Fig. 5). The outer shear member P' is in other respects similar to and of the same length and width as the member P and is interchangeable therewith.

In both outer shear members the planes of arcuate curvature of the inner surfaces of the members for the lengths of their shearing zones may normally conform to and be concentric with the peripheral arcs of the inner cutter blades, or said planes may normally be on a longer radius and eccentric with said arcs of the cutter blades and conformed to the peripheries of the cutter blades by forcing means initially arcuately flexing the members on the peripheries of the blades. Because tensing the outer shear members tends to increase their firmness locally as well as generally, it is believed preferable to initially seat the members flexed and tense, even if only slightly so.

Since the outer shear members P and P' are on opposite sides of the shearing head, radially opposite each other, it is clear that only one of said members is in hair-shearing engagement on the skin at a given time, and, consequently, to hold friction, wear and heating to a minimum during operation means are provided to conveniently and removably lift either one of the outer shear members out of frictional and bearing engagement with the cutting ends or peripheries of the inner cutter member. In these illustrations it is the member P' which is shown removably lifted out of frictional engagement with the cutter peripheries, and this is accomplished by

means of a rigid shear plate lifter spaced throughout from the movable cutter and provided with a more or less radially extending portion 49 paralleling the inner face of the rear wall member 4 and preferably against a portion of the inner face of the wall. At an outer end the shear plate lifter is provided with a transversely projecting portion 50 which is longitudinally curved arcuately and which is flat transversely, and which may have any suitable length and width. Preferably, the portion 50 is approximately as long as either outer shear member and approximately as wide as the width between the inner surfaces of the opposed rows of fingers, and provided with a suitable number of apertures to admit and/or discharge air for general head cooling purposes and particularly for cooling the blades—their peripheries and sides. At opposite marginal longitudinal ends of the portion 50 the outer surface of the member declines longitudinally to the longitudinal ends of the member providing leading and trailing marginal end portions 51 at opposite ends of the portion 50. The free ends of these marginal portions may have any suitable shape, preferably they are rounded transversely. Intermediate these portions the cylindrically curved portion has its inner surface spaced from the peripheries of the cutter and its outer surface parallel to and against the radially opposite inner surface of the outer shear member; against the outer surface of the shear plate lifter the outer member bears, with the springs 33 on this side expanded and under increased tension. The shear plate lifter may be movably mounted on the head in any suitable and convenient manner and by any suitable means; as shown herein, an annular aperture is provided in its body which receives more or less closely a circularly stepped or flanged portion of the sleeve bearing 23 and on which the lifter is turnable rotatably, being held in position thereon by a suitable collar which in this instance consists of a circularly flanged end on the sleeve bearing. The flanged end of the bearing and the inner face of the wall 4 serve to guide or direct the movement of the lifter. Also through the body of the shear member lifter an additional, smaller opening is provided which closely receives a cylindrical post 52 which at its inner end is fastened against outward longitudinal movement or substantial outward movement by suitable means such as the oppositely bent back portions of a split end providing flanges 53. At its outer end, the opposite end, the post is fastened by a spherical-like knob 54 which is preferably in slideable direct or indirect engagement with the outer or rear face of the platform base portion 3; in some instances I prefer to have the knob in slideable indirect engagement and interpose between it and the platform-base portion suitable tensed resilient means such as a compressed coiled spring or a split spring washer. The knob also serves as the means by which the lifter is moved by the user, any finger of the user sufficing, but the thumb on the gripping hand can be comfortably and conveniently employed, and the knob may be integral with the post, or separable and secured thereto by any suitable means, for example solder or other suitable binding substance. Through the rear wall 4 and through the wall of the platform-base portion 3 are formed relatively narrow, arcuate slots, in registration, in which the post 52 travels, which are considered as a single slot and identified by the reference number 55, the length of which is pref-

erably 180° plus the thickness or diameter of the post it receives, and which is so disposed that each opposite marginal end portion extends beyond the plane of the transverse axis of the head 5 and the planes of the transverse axes of the outer shear members a distance equal to, or approximately equal to, one half the thickness or diameter of the post 52. To bring the outer shear member P' into co-operating shear-cutting engagement with the inner cutter member, the shear plate lifter is rotated anti-clockwise and the springs and holding and forcing bars pull the member against the peripheries of the inner cutter member, the pins or studs 40 serving as guiding means and also as stops against longitudinal movement of the shear member with the lifter; when the post 52 has reached the opposite end of the arcuate slot 55 the lifter is in the diametrically opposite position and the outer shear member P is similarly lifted out of frictional engagement with the inner cutter member, the lifter having been brought into nice, smooth progressive engagement with the member P by the inclination of the marginal portion 51 at the leading end of the lifter. It will be observed that lifting an outer shear member without unfastening the springs is not only convenient and simple but also enables the shear member by the pressure it exerts to keep the lifter in the desired position. It is important also to note that the construction and dimensions of the shear plate lifter are preferably such as to provide a suitably effective guard at either side of the head to protect the cutter and its edges and to protect user and/or the person upon whose skin the machine is used from injury by the cutter when only one outer shear member is present in the head, with the result that the machine may be safely and effectively used, with less functional advantage, with either outer shear member omitted.

In some instances suitable equivalent means may be substituted for the pin or stud 40 and slot 33, 33a arrangement heretofore described, for example the wall portions 6 and 12 may each be provided centrally with short, radial slots which receive laterally bent, outwardly projecting finger portions of oppositely and centrally disposed fingers provided on the outer shear members.

Referring to the outer shear member P, and more particularly to the fingers and slots 41 and 42: the inner closed ends of these slots and the edges at the ends can be parallel to the cutter edge with which these shear edges co-operate, as is shown in Fig. 9 wherein the modified shear member PM is provided with fingers 41a having one of their long sides shorter than the other on opposite sides of the slots 42a, the inner ends of which slots 42b are parallel to the co-operating edge of the cutter; or, if desired, the ends 42b may be acutely inclined to the cutter co-operating edge and to the axis of rotation; or, if desired, the inner ends of the slots may be curved as shown in Fig. 10 in which the sides of the fingers spaced by the slots 42c meet to close the ends of the slots on a concave curve 42d. Further, in some instances, at additional cost, the thickness of the extremely thin material of the shear member P, in the region or area of the small openings or short slots 43, is further reduced in parts of said area and a transverse series of longitudinal, concave channels extending lengthwise on the outer surface of the member is provided, such a modification being illustrated in Fig. 11 and in which, to keep cost low, the concave channels R of the outer shear member PM

are, preferably, each as wide as, or approximately as wide as, the transverse width of two spaced rows of small openings or slots and which have their shoulders on the outer surface of transversely alternate longitudinal strips T of the material spacing the rows transversely and their deepest portions longitudinally central with alternate and thinner strips T' of the material transversely spacing the rows. These channels may extend any suitable distance on the member, and, as is believed to be clear, extend in a direction transversely to the axis of the handle and the machine as a whole. Also, in some instances, I may prefer to incorporate in the outer shear members P , PM , PM' and PM'' certain features shown and described in the member P' , for example the elongated hair-receiving slots 45 at opposite marginal longitudinal ends of said member and a suitable number of the fingers and slots $38a$ and $39a$ in these regions; such a modification is illustrated in Fig. 12 in which the outer shear member PP' is provided for the greater part of its length with an intermediate portion having fingers and slots $41'$ and $42'$ corresponding respectively to the similar fingers and slots 41 and 42 , and small openings or short slots $43'$ corresponding to the similar openings 43 , of the member P ; and, further, provided at opposite ends of the rows of fingers and slots $41'$ and $42'$ with spaced fingers $38'$ corresponding to the similar spaced fingers $38a$, and at opposite longitudinal ends of the intermediate portion with elongated hair-receiving slots $45'$, comb teeth $47'$, free ends $48'$ on the teeth, on comb members $46b$ secured to stiffening members $28b$ provided with upwardly and outwardly turned, or hooked, portions $30b$ to receive the holding and forcing bars $31a$, corresponding respectively to the similar parts of the member P' heretofore described.

Referring again to the outer shear member P' , the thickness of the extremely thin material in the region or area of the small openings or short slots 44 , may, in some instances, at additional cost, be further reduced in parts of said area by the provision of a longitudinal series of transverse, concave channels extending width-wise on the outer surface of the member; such a modification is illustrated in Fig. 13 and in which to keep cost low, the concave channels R' of the outer shear member $P'M$ are preferably, each as wide as, or approximately as wide as, the distance longitudinally between two spaced transverse rows of small openings or slots, and which channels have their shoulders on the outer surface of longitudinally alternate, transverse strips Ta of the material spacing the rows longitudinally and their deepest portions transversely central with alternate and thinner strips Tb of the material longitudinally spacing the rows. This series of transverse channels may extend lengthwise of the member any suitable distance intermediate the inner or forward ends of the elongated hair-receiving slots at opposite marginal longitudinal ends of the member, and, as is believed to be clear, the channels extend in a direction longitudinal with the axis of the handle and the machine as a whole.

In Figure 14, the invention is shown as embodied in a head of frusto-conical form, the parts being similar in other respects, and cooperating similarly to, the parts described in the cylindrical head.

In some instances the holding and forcing bars may be provided in the form illustrated in Fig. 15, in which the bars are generally designated

by $31a$ and have cylindrical middle portions $31b$ which are received in the grooves of, and co-operate with the outwardly turned ends of the stiffening members of, the outer shear members. These middle portions have the same lengths, or very close approximations in length, as the grooves, and at opposite marginal ends adjacent the longitudinal ends have raised cylindrical portions $31c$ provided on their inner ends with annular flanged portions whose faces $31d$ project perpendicularly, and with annular shoulders $31e$ which incline upwardly and outwardly, as on a bevel, as shown, or, if desired, the shoulders may be convexly curved. The outer shear members at the ends of their respective grooves are closely received between the flanged portions with the faces $31d$ preferably against, or approximately so, the side ends of the material which form opposite ends of the grooves so that the shear member stops, or very closely limits, longitudinal movement of the bars relative to the shear members, the annular shoulders facilitating seating or reseating of the bars in their respective grooves. The raised cylindrical portions $31c$ have sufficient, and preferably precisely sufficient, lengths relative to the thickness in these regions of the head walls 4 and 13 and the cross-sectional thickness of the encased coil springs to provide narrow annular grooves $31f$, adjacent the cylindrical flanged or disc ends $32a$, to receive the hooked or looped ends of the springs and position the springs in straight planes perpendicular to the bars, the grooves being deep enough and suitably shaped in cross-section to prevent, or substantially prevent, relative lateral movement of the fastening ends or loops of the springs.

I wish it to be understood that the dimensions which have been given are set forth as concrete examples in a preferred illustration and are not to be construed in any sense as a limitation of the scope or relationship of parts of the invention.

Preferably the motor is relatively powerful, and powerful enough to revolve the cutter at a suitably rapid and uniform, or substantially uniform, rate of speed.

I wish it to be understood that in the claims the use of the word "radius" in the singular form in reference to the flexing of the outer shear members to conform their shearing zones to the arc of the inner cutter is not to be construed as a limitation, but rather is to be construed in the broad sense to include the plural form as well.

The invention is susceptible to variations in structure, proportions and minor details without departure from the spirit and scope of the invention, and, having described for purposes of illustration and not for limitation a preferred embodiment, I claim:

1. In a dry shaving head, the combination of an inner cutter movably mounted for arcuate travel, an outer shear member provided with an arcuate shearing zone adapted to co-operate with the inner cutter, a longitudinal area of small hair-receiving openings provided in the shearing zone, elongated hair-receiving slots in the shearing zone in a row at a lateral side of the area of small openings, said row being directed transversely of the direction of curvature of the outer shear member and said slots being directed in the direction of curvature of said outer shear member, comb teeth at the sides of said slots and having combining ends facing in the direction of the area of small openings and having outer surfaces in a higher plane relatively than

the plane of the outer surface of the material in the said area of small openings, and shearing means in said inner cutter disposed in said head for co-operative cutting action with the shearing edges in said shearing zone.

2. In a dry shaving head, the combination of an inner cutter movably mounted for arcuate travel, an outer shear member internally channelled in the direction of arcuate travel of the inner cutter and provided with a resilient arcuate shearing zone formed in sheet metal and adapted to co-operate with the inner cutter, rearwardly depending longitudinally spaced teeth on opposite arcuate sides of the outer member laterally of the shearing zone, means supporting the outer member radially movable relatively to the cutter, means to move radially inwardly and to arcuately flex inwardly the outer member to reduce the radius of curvature of its arcuate shearing zone during wear of the co-operating shear-cutting members, and shearing means in said inner cutter disposed in said head for co-operative cutting action with the shearing edges in said shearing zone.

3. In a dry shaving head, the combination of an inner cutter movably mounted for arcuate travel, an outer shear member provided with an arcuate shearing zone adapted to co-operate with the inner cutter, a longitudinal area of small hair-receiving openings provided in the shearing zone, elongated hair-receiving slots in the shearing zone in a row at a lateral side of the area of small openings, said row being directed transversely of the direction of curvature of the outer member and said slots being directed in the direction of curvature of said outer shear member, comb teeth at the sides of said slots and having combing ends facing in the direction of the area of small openings and having outer surfaces in a higher plane relatively than the outer surface of the material in the area of small openings, rearwardly depending longitudinally spaced guard teeth on the outer member at opposite arcuate sides of said member and laterally of the shearing zone, and shearing means in said inner cutter disposed in said head for co-operative cutting action with the shearing edges in said shearing zone.

4. In a dry shaving head, the combination of an inner cutter movably mounted for arcuate travel, an outer shear member internally channelled in the direction of arcuate travel of the inner cutter and provided with a resilient arcuate shearing zone formed in sheet metal and adapted to co-operate with the inner cutter, rearwardly depending longitudinally closely spaced guard teeth on opposite arcuate sides of the outer shear member laterally of its shearing zone, said guard teeth having differential width and being narrowed in the direction of their free ends, means supporting the outer shear member with its shearing zone arcuately flexed and radially movable relatively to the inner cutter, means to move radially inwardly and to arcuately flex inwardly the outer member to reduce the radius of curvature of its arcuate shearing zone during wear of the co-operating shear-cutting members, and shearing means in said inner cutter disposed in said head for co-operative cutting action with the shearing edges in said shearing zone.

5. In a dry shaving head, the combination of an inner cutter movably mounted for arcuate travel, an outer shear member internally channelled in the direction of arcuate travel of the

inner cutter and provided with a resilient arcuate shearing zone formed in sheet metal and adapted to co-operate with the inner cutter, a longitudinal area of closely grouped small hair-receiving openings in said shearing zone, a longitudinal row of hair-receiving slots in said shearing zone at opposite sides of said area of small openings, the rows being directed in the direction of curvature of the outer member and

5 the slots being directed transversely to the direction of curvature of the outer member, said slots having their inner ends closed and their outer ends open and having rearwardly extending portions longitudinally closely spacing rearwardly depending guard teeth at opposite arcuate sides of the outer member laterally of the shearing zone, said guard teeth being of tapered width narrowed rearwardly to their free ends, means supporting the outer shear member with its shearing zone arcuately flexed and radially movable relatively to the inner cutter, means to move radially inwardly and to arcuately flex inwardly the outer member to reduce the radius of arcuate curvature of its shearing zone during wear of the co-operating shear-cutting members, and shaving means in said inner cutter disposed in said head for co-operative cutting action with the shearing edges in said shearing zone.

6. In a dry shaving head, the combination of an inner cutter movably mounted for arcuate travel, an outer shear member internally channelled in the direction of arcuate travel of the inner cutter and provided with a resilient arcuate shearing zone formed in sheet metal and

30 adapted to co-operate with the inner cutter, a longitudinal area of closely grouped small hair-receiving openings in said shearing zone, elongated hair-receiving slots in the shearing zone in a row at opposite lateral sides of the area of

35 said small openings, said rows being directed transversely to the direction of curvature of the outer shear member and said slots being elongated in a direction transverse to the direction of said rows, comb teeth at the sides of said slots

40 and facing in the direction of the area of small openings and having outer surfaces in a higher plane relatively than the plane of the outer surface of the material in the area of small openings, a longitudinal row of hair-receiving slots

50 at transversely opposite sides of said area of small openings, these rows being directed in the direction of curvature of the outer member and the slots being directed transversely to the direction of curvature of the outer member, said latter slots having their inner ends closed and their outer ends open and having rearwardly extending portions longitudinally closely spacing rearwardly depending guard teeth on opposite arcuate sides of the outer member laterally of the

55 shearing zone, said guard teeth being of tapered width narrowed rearwardly to their free ends, means supporting the outer shear member with its shearing zone arcuately flexed and radially movable relatively to the inner cutter, means

60 to move radially inwardly and to arcuately flex inwardly the outer member to reduce the radius of arcuate curvature of its shearing zone during wear of the co-operating shear-cutting members, and shearing means in said inner cutter disposed in said head for co-operative cutting action with the shearing edges in said shearing zone.

65 7. In a shaving machine, the combination of an inner cutter movably mounted for arcuate travel, an outer shear member internally chan-

nnelled in the direction of arcuate travel of the inner cutter and provided with a resilient arcuate shearing zone adapted to co-operate with the inner cutter and formed in extremely thin sheet metal intermediate oppositely disposed marginal end portions of said sheet metal, said shearing zone including a longitudinal area of closely grouped small hair-receiving openings and at opposite lateral sides of said area a row of elongated hair-receiving slots, said rows of elongated slots being directed transversely to the direction of curvature of the outer shear member and said slots being elongated in a direction transverse to the direction of said rows and being individually of relatively greater width than said closely grouped small hair-receiving openings, said shearing zone also including a longitudinal row of hair-receiving slots at other opposite sides of said area of small openings, these rows being directed in the direction of curvature of the outer member and the slots being directed transversely to the direction of curvature of the outer member, said latter slots having their inner ends closed and their outer ends open and having rearwardly extending portion longitudinally closely spacing rearwardly depending guard teeth on opposite arcuate sides of the outer member laterally of the shearing zone, said guard teeth being of tapered width narrowed rearwardly to their free ends, stiffening members of relatively rigid material superimposed on the outer face of the marginal end portions of sheet metal and united with said portions, outwardly hooked ends at the outer ends of the stiffening members, resilient comb teeth in planes at the sides of said elongated slots and faced in the direction of the area of small openings, said teeth bearing on the outer member in planes laterally of the elongated slots and having outer surfaces in a higher plane relatively than the plane of the outer surface of the material in the area of small openings, resilient holding and forcing means engaging the hooked ends of the outer member and movably supporting said member with its shearing zone flexed in arcuate form and pressed against the inner cutter and serving, during wear of the co-operating shear-cutting members, to move the outer shear member radially inwardly and to flex the outer member to reduce the radius of curvature of its arcuate shearing zone, and shearing means in inner cutter disposed for co-operative cutting action with the shearing edges in said shearing zone.

8. In a shaving machine the combination as claimed in claim 7 and means co-operative with means centrally disposed longitudinally on the arcuate side of the outer shear member to substantially prevent, longitudinal movement of said member by the arcuate travel of the inner cutter.

9. In a shaving machine, the combination of an inner cutter movably mounted for arcuate travel, an outer shear member provided with a resilient arcuate shearing zone adapted to co-operate with the inner cutter, resilient holding and forcing means engaging the outer shear member for movably holding said outer member with its shearing zone seated against the inner cutter, said holding and forcing means including a rigid bar extending transversely of the direction of curvature of the outer shear member, said bar provided with a longitudinally extending middle portion received by the outer shear member in a groove directed transversely to the direction of curvature of said outer shear member, raised portions on said bar at opposite marginal

5 ends providing annular flanges for closely receiving the material of the outer shear member at opposite ends of the groove to substantially prevent, relative longitudinal movement of the bar in the groove, narrow annular grooves in the raised portions, at their outer ends, receiving, relatively rotatably, fastening means on ends of forcing springs, flanged ends on the bar at the outer ends of the raised portions, and rigid fastening means co-operating with fastening means on the opposite ends of said forcing springs to mount the springs pivotally movable together with said bar.

10. In a shaving machine, the combination of a housing-handle, a cutter-casing on an end of the housing-handle and provided with longitudinally spaced walls having arcuately curved radial end portions on the same opposite sides, a rotary inner cutter movably mounted for travel between the planes of said walls, said inner cutter having a radius of travel of its cutting edges in excess of the radii of curvature of said radial end portions of the cutter-casing whereby the cutting ends of the inner cutter project radially outwardly of said radial end portions of the cutter-casing, an outer shear member internally channelled in the direction of travel of the inner cutter and provided with a resilient arcuate shearing zone formed in extremely thin sheet metal and adapted to co-operate with the inner cutter, said inner cutter provided with cutting edges successively inclined in opposite oblique directions to said shearing zone, a longitudinal area of closely grouped small hair-receiving openings in said shearing zone, elongated hair-receiving slots in the shearing zone in a row at opposite lateral sides of the area of said small openings, said rows being directed transversely to the direction of curvature of the outer shear member and said slots being elongated in a direction transverse to the direction of said rows and being individually of relatively greater width than said closely grouped small hair-receiving openings, comb teeth at the sides of said slots and facing in the direction of the area of small openings and having outer surfaces in a higher plane relatively than the outer surface of the material in the area of small openings, a longitudinal row of hair-receiving slots on other opposite sides of said area of small openings, these rows being directed in the direction of curvature of the outer member and these slots being directed transversely to the direction of curvature of the outer member, said latter slots having their inner ends closed and their outer ends open and having rearwardly extending portions longitudinally closely spacing rearwardly depending guard teeth on opposite arcuate sides of the outer member laterally of the shearing zone, said guard teeth being of tapered width narrowed rearwardly to their free ends, resilient holding and forcing means movably supporting the outer shear member against the inner cutter with its guard teeth in radially telescopic relationship with the walls of the cutter-casing, said holding and forcing means movably supporting said outer shear member with its shearing zone flexed tautly on and pressed against the inner cutter and for retaining said shearing zone flexed tautly on and pressed against the inner cutter during wear of the co-operating shear-cutting members and for reducing the radius of curvature of its arcuate shearing zone during said wear, and means to substantially prevent, longitudinal movement of

the outer shear member in the direction of travel of the inner cutter.

11. In a shaving machine, the combination of a housing-handle, a cutter-casing on an end of the housing-handle and provided with longitudinally spaced walls having arcuately curved radial end portions on the same opposite side, a rotary inner cutter movably mounted for travel between the planes of said walls, said inner cutter having a radius of travel of its cutting edges in excess of the radii of curvature of said radial end portions of the cutter-casing whereby the cutting ends of the inner cutter project radially outwardly of said radial end portions of the cutter-casing, an outer shear member internally channelled in the direction of travel of the inner cutter and provided with a resilient arcuate shearing zone formed in extremely thin sheet metal and adapted to co-operate with the inner cutter, said inner cutter provided with cutting edges successively inclined in opposite oblique directions to said shearing zone, a longitudinal central area of closely grouped, small, short hair-receiving slots in said shearing zone, said small short slots being directed transversely to the direction of curvature of the outer member, elongated hair-receiving slots in the shearing zone in a row at opposite lateral sides of the central area of short slots, said rows being directed transversely to the direction of curvature of the outer shear member and said slots being elongated in a direction transverse to the direction of said rows and being individually of relatively greater width than said small, short hair-receiving slots, comb teeth in planes at the sides of said elongated slots and having combing ends facing in the direction of the central area of short slots and having outer surfaces in a higher plane relatively than the plane of the outer surface of the material in the central area of short slots, a longitudinal row of hair-receiving slots on other opposite sides of said central area of short slots, these rows being directed in the direction of curvature of the outer member and these slots being directed transversely to the direction of curvature of the outer member, said latter slots being longitudinally spaced by comb bars of relatively thicker material than the material in said central area of closely grouped, small short slots and having their inner ends closed in said shearing zone and their outer ends open and having rearwardly extending portions longitudinally closely spacing rearwardly depending guard teeth on opposite arcuate sides of the outer member laterally of the shearing zone, said guard teeth being of tapered width narrowed rearwardly to their free ends, resilient holding and forcing means movably supporting the outer shear member against the inner cutter with its guard teeth in radially telescopic relationship with the walls of the cutter-casing, said holding and forcing means movably supporting said outer shear member with its shearing zone flexed tautly on and pressed against the inner cutter and for retaining said shearing zone flexed tautly on and pressed against the inner cutter during wear of the co-operating shear-cutting members and for reducing the radius of curvature of its arcuate shearing zone during said wear, and means to substantially prevent, longitudinal movement of the outer shear member in the direction of travel of the inner cutter.

12. In a shaving machine, the combination of a housing-handle, a cutter-casing on an end of the housing-handle and having opposite sides

arcuately open and radially disposed relatively to the axis of the housing-handle, a rotary inner cutter movably mounted for travel in the cutter-casing, an outer shear member protectively closing one of said opposite open sides of the cutter-casing and radially disposed relatively to the inner cutter, and provided with an arcuate shearing zone adapted to co-operate with the inner cutter, means supporting the outer shear member radially movable to the inner cutter during wear of the co-operating shear-cutting members and radially movable in the opposite direction, and a pivotally mounted member manipulatively movable from one radial side of the cutter-casing to the other positioned to protectively close the side of said cutter-casing radially opposite said outer shear member and having means to movably engage and lift said outer shear member out of frictional engagement with the inner cutter.

13. In a shaving machine, the combination of an inner cutter movably mounted for rotary travel, a plurality of outer shear members provided with longitudinal areas of closely grouped small hair-receiving openings formed in sheet metal in arcuate shearing zones of the substantially same thinness in cross-section and adapted to co-operate with the inner cutter in frictional contact therewith, spaced slots in the shearing zone of one of said outer shear members relatively larger than said small openings thereof and extending in the direction of curvature of said one of said members at an end of the area of small openings thereof, means movably supporting the outer shear members, means to support either outer shear member radially movable with its arcuate shearing zone pressing against the inner cutter, means supporting one of said outer shear members radially movable with its shearing zone pressing against said inner cutter, and manipulatively movable means to lift and removably hold either of said outer shear members with its shearing zone out of frictional contact with the inner cutter and removably holding one of said outer shear members out of said contact with the inner cutter.

14. In a shaving machine, the combination of an inner cutter movably mounted for rotary travel, a plurality of outer shear members provided with arcuate shearing zones adapted to co-operate with the inner cutter in frictional contact therewith, means movably supporting the outer shear members, means to support either outer shear member radially movable with its arcuate shearing zone pressing against the inner cutter, means supporting one of said outer shear members radially movable with its arcuate shearing zone pressing against the inner cutter, and pivotally mounted manipulatively movable means to lift and removably hold either of said outer shear members with its shearing zone out of frictional contact with the inner cutter and removably holding one of said outer shear members out of said contact with the inner cutter, said manipulatively movable means provided with a longitudinal portion arcuately overhanging the inner cutter and having its outer side convexly curved for engagement with the concavely curved surface of the shearing zone of either outer shear member.

15. In a shaving machine, the combination of an inner cutter movably mounted for rotary travel, a plurality of outer shear members provided with arcuate shearing zones adapted to co-operate with the inner cutter in frictional contact therewith and provided with marginal end

portions depending in said outer shear members tangentially to said arcuate shearing zones thereof and radially spaced from said inner cutter, means movably supporting the outer shear members, means to support either outer shear member radially movable with its arcuate shearing zone pressing against the inner cutter, means supporting one of said outer shear members radially movable with its arcuate shearing zone pressing against the inner cutter, pivotally mounted manipulatively movable means to lift and removably hold either of said outer shear members with its shearing zone out of frictional contact with the inner cutter and removably holding one of said outer shear members out of said contact with the inner cutter, said manipulatively movable means provided with a longitudinal portion arcuately overhanging the inner cutter and having its outer side convexly curved for engagement with the concavely curved surface of the shearing zone of either outer shear member, said arcuately overhanging portion having downwardly curved outer side portions at opposite longitudinal ends thereof, and the outer ends of said downwardly curved portions being in a lower plane than the inner surface of an adjacent one of said marginal end portions depending tangentially in the outer shear member having its arcuate shearing zone in contact with the inner cutter.

16. In a shaving machine, the combination of a housing-handle, a cutter-casing on an end of the housing-handle and provided with longitudinally spaced walls having radial end portions arcuately curved transversely to the axis of the machine on radially disposed sides of the cutter-casing, a rotary inner cutter movably mounted for travel between the planes of said walls, arcuate peripheral cutting edges obliquely inclined relatively close to a right angle to the axis of rotation provided in said inner cutter, said inner cutter having a radius of travel of its cutting edges in excess of the radii of curvature of said radial end portions of the cutter-casing whereby the cutting ends of the inner cutter project radially outwardly of said radial end portions of the cutter-casing, a plurality of outer shear members internally channelled in the direction of travel

of the inner cutter and provided with resilient arcuate shearing zones formed in extremely thin sheet metal and adapted to co-operate with the inner cutter in frictional contact therewith, one 5 of said outer shear members having in its shearing zone a central longitudinal area of closely grouped small hair-receiving openings transversely intermediate longitudinal rows of hair-receiving slots, said rows being directed in the 10 direction of curvature of said outer shear member at opposite sides of the central area of small openings and said slots being directed transversely to the direction of said rows and having their inner ends closed and their outer ends 15 open and having rearwardly extending portions longitudinally spacing rearwardly depending guard teeth on opposite arcuate sides of the member laterally of its shearing zone; the other of said outer shear members having in its shearing zone a longitudinal area of closely grouped small hair-receiving openings, said latter area including at the lateral side of the shearing zone longitudinally outermost of the housing-handle an arcuate row of small hair-receiving openings 20 closely adjacent the side end of the member, rearwardly depending longitudinally spaced guard teeth on opposite arcuate sides of said outer shear member laterally of its shearing zone; means movably supporting the outer shear members, means to support either outer shear member radially movable with its shearing zone pressing against 25 said inner cutter, and pivotally mounted manipulatively movable means to lift and removably hold either of said outer shear members with its shearing zone out of frictional contact with the inner cutter and removably holding one of said outer shear members out of said contact with the inner cutter, said manipulatively movable means provided with a longitudinal portion overhanging the inner cutter and having its outer side convexly curved for engagement with the concavely curved surface of the shearing zone of 30 either outer shear member.

JOHN T. SCULLY.

CERTIFICATE OF CORRECTION.

Patent No. 2,359,880.

October 10, 1944.

JOHN T. SCULLY.

It is hereby certified that error appears in the printed specification of the above numbered patent requiring correction as follows: Page 2, second column, line 3, for "suitble" read --suitable--; page 3, second column, line 9, for "to the ends" read --of the ends--; page 8, second column, line 73, claim 1, for "combining" read --combing--; page 9, second column, line 26, claim 5, for "shaving" read --shearing--; and that the said Letters Patent should be read with this correction therein that the same may conform to the record of the case in the Patent Office.

Signed and sealed this 23rd day of January, A. D. 1945.
